(57) **CLAIM**

The ornamental design for a bracket for a roof rack storage unit, as shown and described.

DESCRIPTION

FIG. 1 is a front view of a bracket for a roof rack storage unit in accordance with the present invention;

FIG. 2 is a right-side view of the bracket for a roof rack storage unit of FIG. 1;

FIG. 3 is a rear view of the bracket for a roof rack storage unit of FIGS. 1 and 2;

FIG. 4 is a left-side view of the bracket for a roof rack storage unit of FIGS. 1-3;

FIG. 5 is a bottom view of the bracket for a roof rack storage unit of FIGS. 1-4;

FIG. 6 is a top view of the bracket for a roof rack storage unit of FIGS. 1-5;

FIG. 7 is a bottom perspective view of the bracket for a roof rack storage unit of FIGS. 1-6; and,

FIG. 8 is a top perspective view of the bracket for a roof rack storage unit of FIGS. 1-7.

The broken lines depict portions of the bracket for a roof rack storage unit that form no part of the claimed design.
